(57) **CLAIM**

The ornamental design for a holder with fluid drainage for toothbrushes and other dental care items, as shown and described.

DESCRIPTION

FIG. 1 is a perspective view showing the top, left side and rear of a holder with fluid drainage for toothbrushes and other dental care items which forms my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a right side elevational view thereof;

FIG. 7 is a left side elevational view thereof; and,

FIG. 8 is a perspective view showing the top, right side and front thereof.
